CLAIM

The ornamental design for a mechanical housing for an emission monitoring device, as shown and described.

DESCRIPTION

FIG. 1 is a left view of a mechanical housing for an emission monitoring device;

FIG. 2 is a front view thereof;

FIG. 3 is a right view thereof;

FIG. 4 is a top view thereof with a solar panel;

FIG. 5 is a left side perspective view thereof;

FIG. 6 is a right side perspective view thereof;

FIG. 7 is an additional right side perspective thereof; and,

FIG. 8 is an exploded view thereof.

The dot-dash line in FIG. 8 illustrates the order of assembly of the mechanical housing for an emission monitoring device and forms no part of the claim. The bracket enclosing the exploded view in FIG. 8 forms no part of the claim.
